TOM SUTCLIFFE, OF LONDON, ENGLAND.

CONCRETE OR LIKE BUILDING BLOCK AND METHOD OF MAKING THE SAME.

1,316,521.

Specification of Letters Patent. Patented Sept. 16, 1919.

Application filed June 23, 1919. Serial No. 306,235.

To all whom it may concern:

Be it known that I, TOM SUTCLIFFE, a subject of the King of Great Britain, and resident of London, England, have invented a new and useful Improvement in Concrete or like Building Blocks and Methods of Making the Same, of which the following is a specification.

This invention relates to an improved construction of hollow concrete or like building blocks and to a method of making the same.

My improved block is molded as a whole with full faces on all its aspects and a cavity or cavities in its interior, such cavity or cavities being so determined that each wall of the block is of uniform and predetermined thickness throughout.

The method of manufacture, according to my invention, is an improvement on the known methods of molding hollow blocks in which sand is used as a means of forming the cavities or in which core boxes are used that are left in the finished block.

In making my improved block I employ a mold of any suitable known kind which can be dismantled and a core which can be removed through holes in the walls of the block after the block is molded, the shape of the core being determined by a liner which is removed before the molding operation is completed. The holes aforesaid are formed during the molding of the block. A suitable material for forming the core is loose sand which can be readily extracted from the block by an air blast or otherwise.

The accompanying drawing illustrates, by way of example, a rectangular block constructed according to my invention and a convenient form of mold used for making the same.

Figure 1 is a perspective view of the block, the hollow interior being indicated by broken lines.

Figs. 2 and 3 are transverse and longitudinal sections of the block taken on the lines X, X, and Y, Y respectively.

Fig. 4 is a perspective view of a mold in which the block is made, the top plate of the mold being removed.

Fig. 5 is a perspective view of a core box or liner hereinafter described, and

Fig. 6 shows a pin used for making the extraction holes in the walls of the block.

The block A as shown in Figs. 1, 2 and 3 has full faces on all sides, and is hollow,

the thickness of the walls of the block being suited to the load to be carried. B, B are holes in two opposite walls of the block. It will be understood that the holes may occupy any convenient position in the faces of the block.

The mold shown in Fig. 4 is constituted by a bottom board or plate C, side walls D, D, and end walls E, E, the walls being held firmly together when assembled by bolts J, J in the usual manner. The opposite pair of walls D, D are perforated at F, F to receive pins such as G, Fig. 6. H is a core frame or liner made, for example, of thin metal having four sides and open at the top and bottom, the size of said frame being equal to the desired size of the interior hollow space to be formed in the block.

The method of making the block is as follows:—The bottom plate C, end plates E, E and side plates D, D of the mold are assembled so that they form a box-like structure with an open top, as seen in Fig. 4. A layer of concrete mixture, of any desired thickness, is then made to cover the bottom plate C. The frame or liner H is then placed in the box so that it rests on the layer of concrete and occupies a position equidistant from the sides and ends of the box. The pins G, G are now passed through the holes F, F until their inner ends touch the liner H, after which the space between the liner and the inside of the box is filled in with concrete, thus forming the walls of the block. The inside of the liner is filled with loose sand which is pressed or rammed tight to form a perfect core, and the liner is then withdrawn. After such withdrawal a final layer of concrete is then put over the whole and the top plate of the box (not shown) is fixed in position so that the desired finish is given to that face.

It will be obvious that any form of reinforcing metal or other material can be introduced into the walls of the block during the operation of forming the same in order to strengthen the finished block. When the concrete has set, the pins G, G are withdrawn, and the block is removed from the box or mold. The sand core is then extracted through the holes F, F formed by the pins. A convenient mode of extracting the sand core is by means of an air blast. If desired, the holes in the block can be plugged after the sand has been removed. In lieu of a liner such as H, I may in some cases use a card,

board or paper bag or the like stiffened, if necessary, by corrugations or ribs and filled with sand to form the core, from which the sand can be removed after the block is set, 5 in the same manner as that employed in the case of the liner. In this case the bag would be left in the block. Holes can be made in such a liner for the removal of the sand. The holes F, F are shown opposite 10 one another in Fig. 4, but this arrangement of the holes is not essential.

If desired, two or more independent cores 15 may be used so as to produce two or more cavities in the block, which might be desirable when great strength is required or when the blocks are of large size.

The block shown in Fig. 1 has plain faces, 20 but it will be obvious, since the mold is of the kind that can be dismantled, that any desired impression can be imposed on these faces by suitably shaping the walls of the mold. For example, pieces can be arranged 25 in the mold to form grooves or tongues on the sides or ends of the block, or a bevel can be similarly formed on the edges of the block.

I claim:

1. A method of molding a hollow concrete or like building block consisting in 30 forming a layer of concrete or the like on the bottom of a mold, placing thereon a hollow liner (H) having the shape of the cavity to be formed in the block, inserting pins (G, G) through the sides of the mold to 35 touch the liner, forming the side walls of the block by filling with concrete the space between the liner and the side walls of the mold, filling the liner with sand, then withdrawing the liner, and placing a layer of 40 concrete over the top to complete the block, and applying the lid of the mold, then when the concrete has set withdrawing the pins (G, G), removing the block from the mold, and extracting the sand core from the 45 interior of the block.

2. A method of molding a hollow concrete or like building block consisting in forming a layer of concrete or the like having 50 reinforcing material therein on the bottom of a mold, placing thereon a hollow liner (H) having the shape of the cavity to be formed in the block, inserting pins (G, G) through the sides of the mold to

touch the liner, forming the side walls of the block by filling with concrete having reinforcing material therein the space between the liner and the side walls of the mold, filling the liner with sand, then withdrawing the liner, and placing a layer of concrete having reinforcing material therein over the top to complete the block, and applying the lid of the mold, then when the concrete has set withdrawing the pins (G, G), removing the block from the mold, and extracting the sand core from the interior of the block. 55

3. A method of molding a hollow concrete or like building block consisting in forming a layer of concrete or the like on the bottom of a mold, placing thereon a hollow liner (H) having the shape of the cavity to be 60 formed in the block, inserting pins (G, G) through the sides of the mold to touch the liner, forming the side walls of the block by filling with concrete the space between the liner and the side walls of the mold, filling the liner with sand, then withdrawing the liner and placing a layer of concrete over the 65 top to complete the block, and applying the lid of the mold, then when the concrete has set withdrawing the pins (G, G), removing the block from the mold, and extracting the sand core by means of a sand blast from the interior of the block.

4. A hollow concrete or like building block having full faces on all its aspects and walls 70 of uniform thickness formed by applying a layer of concrete in the bottom of a mold placing thereon a hollow liner having the shape of the cavity to be formed in the block, inserting pins through the sides of 75 the mold to touch the liner, forming the side walls of the block by filling with concrete the space between the liner and the side walls of the mold, filling the liner with sand, then withdrawing the liner and placing a 80 layer of concrete over the top to complete the block, and applying the lid of the mold, then when the concrete has set withdrawing the pins, removing the block from the mold, and extracting the sand core from the 85 interior of the block.

TOM SUTCLIFFE.
